TABLE

Aaron S. Goldberg, Philadelphia, Pa., assignor to
Bunting Glider Company, Philadelphia, Pa., a
corporation of Pennsylvania

Application September 10, 1949, Serial No. 4,948

Term of patent 14 years

(Cl. D33—14)

To all whom it may concern:

Be it known that I, Aaron S. Goldberg, a citizen of the United States, and a resident of Philadelphia, county of Philadelphia, State of Pennsylvania, have invented a new, original, and ornamental Design for a Table, of which the following is a specification, reference being had to the accompanying drawing, forming a part thereof, wherein:

Figure 1 is a perspective view of a table, showing my new design;

Figure 2 is a horizontal sectional view as taken on the line 2—2 of Figure 1; and

Figure 3 is a fragmentary cross-sectional view of the table top.

I claim:

The ornamental design for a table, as shown.
AARON S. GOLDBERG.
